APPARATUS FOR MAKING POMPONS.

Ralph R. Cone, New York, N. Y., assignor to Lily Mills Company, Shelby, N. C., a corporation of North Carolina

Application November 16, 1940, Serial No. 365,895.

8 Claims. (Cl. 28—2)

This invention relates to a device for making fabric ornamentation such as tufts, pompons, rosettes and the like and more especially to an apparatus which is adapted to hold a skein of stretched strand material while it is tied and severed at spaced points to form the above-named ornamentation.

It is desirable to have a pile or tufted finish on many articles such as rugs, seat covers and the like, not only for ornamental purposes but also to provide a softer and more durable wearing surface. When pompons, tufts and the like are used, however, almost any color pattern may be used since the individual tufts or pompons are usually tied by hand onto a suitable ground fabric.

It is an object of this invention to provide a simple apparatus for holding a strand or strands of yarn in a taut condition, and for confining the same with the intermediate portion thereof is tied and severed at predetermined points to form tufts, pompons and the like. Specifically the invention comprises an elongated trough-like member having pins disposed at each end thereof around which a skein of yarn is wound. The intermediate portion of the skein is adapted to removably fit in the trough and the trough has a plurality of transverse slots in the sidewalls for accommodating tie strings and also has other transverse slots in the sidewalls between the tie string grooves for accommodating a knife or other cutting tool to sever the tied skein. Such an apparatus permits the skein to be formed on the upper portion of the pins and then to be pushed downwardly into the trough where the tying and severing operations take place.

Some of the objects of the invention having been stated, other objects will appear as the description proceeds, when taken in connection with the accompanying drawing, in which—

Figure 1 is an isometric view of my improved device upon which tufts, pompons, rosettes and the like are adapted to be formed;

Figure 2 is an isometric view similar to Figure 1 with the central portion thereof broken away showing a skein of yarn or other tufting material supported by the apparatus and also showing suitable tie strings disposed at spaced points for subsequently tying the skein intermediate its ends;

Figure 3 is an isometric detail view of a part of the device showing the skein of yarn after it has been lowered from the position shown in Figure 2 and after it has been tied by the tie strings;

Figure 4 is an isometric detail view showing the positions of the ends of the tie string after the skein has been tied and also showing a suitable blade inserted in one of the transverse slots in the apparatus for severing the tied skein intermediate the tie points;

Figure 5 is an isometric view of a portion of the skein after it has been severed and tied to form a separate bunch of yarn;

10. Figure 6 is a view of Figure 5 after the severed tied ends have been fluffed and finished;

Figure 7 is a face view of one of the finished tufts, pompons, and the like.

Referring more specifically to the drawing, the numeral 10 denotes a suitable elongated base member which is adapted to rest upon any suitable support such as a table. Upon the upper surface of the base member 10 is secured a longitudinally disposed trough-like member 11 having spaced sidewalls 13, said member 11 having its bottom portion extending substantially beyond the ends of the sidewalls forming portions 11a, which portions 11a support vertically disposed pins 12. It will be noted that these pins are substantially higher than the sidewalls of the trough member 11. The purpose of providing this additional height of the pins is to permit a suitable skein of yarn 14 to be wound around the upper portions of the pins and at the same time clear the tops of the trough sidewalls.

The sidewalls 13, have a plurality of sets of transverse slots 15 therein, said slots extending from the top edges of the sidewalls to the bottom portion of the trough. These slots are 35 disposed in pairs so that a single tie string 16 can be inserted in two coinciding slots thereby permitting the intermediate portion of the tie string to be disposed on the bottom of the trough while the ends overhang each side of members 40 10 and 11 (Figure 2).

The trough 11 is equipped with a plurality of other sets of slots 17 which are disposed between the tie strings slots 15. The purpose of these slots is illustrated in Figure 4 where it is seen that a suitable cutting mechanism such as a knife blade 18 is adapted to be inserted into pairs of these slots to sever the tied skein intermediate the tie points. Scissors can also be used as a cutting tool, if desired.

50. When using the above described apparatus for forming tufts, a suitable skein of yarn 14 is wound around the upper portions of the pins 12 (Figure 2). Upon the completion of the skein and its ends secured, it is pushed downwardly toward the bases of the pins and into the trough

member 11 to the position shown in Figure 3. The ends of the tie strings 16, which are disposed in the slots 15, are then gathered and suitable knots 20 are tied, and then the two ends of each tie string are pulled toward the observer in Figures 3 and 4 and pressed into one of the slots 15 where the friction of the slots will anchor the ends into position. At this time, the skein is in position for the severing operation which is illustrated in Figure 4. When the skein has been severed at each of the pairs of slots 17, suitable bunches 22 of short strands are formed. These bunches are fluffed and finished to form tufts or pompons 23, as shown in Figures 6 and 7, after which they are ready to be tied or sewed upon a suitable ground fabric to form a rug or other tufted article.

It will be noted that when the severing mechanism 16 is inserted into the alternate slots 17, which are not occupied by the tie strings, that the entire intermediate portion of the skein of yarn will be cut into short lengths. However, the end portions of the skein which extend around the pins 12 will remain unsevered. If desired suitable vertically disposed grooves 25 may be provided in each of these pins to accommodate other tie strings for tying the end tufts. Upon tying the tufts at the ends, it will be necessary to sever the skein at a point adjacent the end of the trough walls 13. By employing this method the entire skein may be utilized for making tufts thereby eliminating any waste. It is obvious that the tufts formed at the pins 12 are slightly different from the tufts formed on the intermediate portion of the skein, since there will be a slightly greater variation in the length of the short strands which form the tied bunch; however, these tufts may be segregated and used for special purposes.

In the drawing and specification, there has been set forth a preferred embodiment of the invention, and although specific terms are employed, they are used in a generic and descriptive sense only and not for purposes of limitation, the scope of the invention being set forth in the appended claims.

I claim:

1. Apparatus for forming tufts, pompons and the like, comprising a horizontal U-shaped trough member adapted to receive the intermediate portion of a skein of tufting material, a pair of spaced upstanding pins alined with the longitudinal axis of the trough, and adapted to support the ends of the skein to hold the same in distended position, said trough having a plurality of pairs of spaced transverse slots in the sidewalls for receiving the intermediate portions of tie strings whereby the skein can be tied at a plurality of spaced points while in the trough.

2. Apparatus for forming tufts, pompons and the like, comprising a horizontal U-shaped trough member adapted to receive the intermediate portion of the skein of tufting material, a pair of spaced upstanding pins alined with the longitudinal axis of the trough, and adapted to support the ends of the skein to hold the same in stretched position, said trough having a plurality of spaced transverse slots in the side walls for receiving the intermediate portions of tie strings whereby the skein can be tied at a plurality of spaced points while in the trough, the trough side walls also having a second set of transverse slots intermediate said string receiving slots to permit a severing mechanism to be inserted

therein for severing the skein between the tied points.

3. Apparatus for forming tufts, pompons and the like comprising an elongated member having a longitudinal groove therein adapted to receive a skein of tufting material, means for removably holding the skein in stretched position in the groove, said groove having a plurality of spaced transverse slots in its sidewalls for receiving the intermediate portions of strings whereby the skein can be tied at a plurality of spaced points while in the groove.

4. Apparatus for forming tufts, pompons and the like comprising a longitudinally grooved member adapted to receive a skein of tufting material, means for removably holding the skein in stretched position in the groove, said groove having a plurality of spaced transverse slots in its sidewalls for receiving the intermediate portions of strings whereby the skein can be tied at a plurality of spaced points while in the groove, the groove sidewalls also having a second set of transverse slots intermediate said string receiving slots to permit a cutting tool to be inserted therein for severing the skein between the tied points.

5. Apparatus for forming tufts, pompons and the like comprising a longitudinally grooved member adapted to receive a skein of tufting material, a pair of pins around which the skein is adapted to be placed for holding the same in stretched position in said groove, said groove having a plurality of pairs of spaced transverse slots in its sidewalls for receiving the intermediate portions of tie strings whereby the skein can be tied at a plurality of spaced points while in the groove.

6. Apparatus for forming tufts, pompons and the like comprising a longitudinally grooved member adapted to receive a skein of tufting material, a pair of pins around which the skein is adapted to be placed for holding the same in stretched position in said groove, said groove having a plurality of pairs of spaced transverse slots in its side walls for receiving the intermediate portions of tie strings whereby the skein can be tied at a plurality of spaced points while in the groove, the groove sidewalls also having a second set of pairs of transverse slots intermediate said string receiving slots to permit a severing mechanism to be inserted therein for severing the skein between the tied points.

7. Apparatus for forming tufts and the like comprising a U-shaped trough member, adapted to receive the intermediate portion of a skein of tufting material, a pair of spaced upstanding pins alined with the longitudinal axis of the trough and adapted to support the ends of the skein to hold the same in stretched position, said pins being substantially higher than the sidewalls of the trough so that the skein can be wound around the upper portion of the pins and subsequently moved into the trough while on the pins, said trough having a plurality of pairs of spaced transverse slots in the sidewalls for receiving the intermediate portions of tie strings, whereby the skein can be tied at a plurality of spaced points while in the trough.

8. Apparatus for forming tufts and the like comprising a U-shaped trough member, adapted to receive the intermediate portion of a skein of tufting material, a pair of spaced upstanding pins alined with the longitudinal axis of the trough and adapted to support the ends of the skein to hold the same in stretched position, said pins be-

ing substantially higher than the sidewalls of the trough, so that the skein can be wound around the upper portion of the pins and subsequently moved into the trough while on the pins, said trough having a plurality of pairs of spaced transverse slots in the sidewalls for receiving the intermediate portions of tie strings whereby

the skein can be tied at a plurality of spaced points while in the trough, each of said pins having a groove for receiving a tie string, so that a tuft can be formed out of the end portions of the skein.

5 RALPH R. CONE.
